UNITED STATES PATENT OFFICE.

GEORGE M. NEWHALL, OF PHILADELPHIA, PENNSYLVANIA, ASSIGNOR
TO THE AMERICAN BARREL AND STAVE COMPANY, OF CAMDEN, NEW
JERSEY.

MACHINE FOR SETTING UP BARRELS.

SPECIFICATION forming part of Letters Patent No. 393,571, dated November 27, 1888.

Application filed March 12, 1888. Serial No. 267,010. (No model.)

To all whom it may concern:

Be it known that I, GEORGE M. NEWHALL, a citizen of the United States, and a resident of Philadelphia, Pennsylvania, have invented 5 certain Improvements in Machines for Setting up Barrels, of which the following is a specification.

The object of my invention is to provide a barrel setting up or trussing machine with 10 means for firmly holding the barrel-head in position while the barrel is being formed, and this object I attain as hereinafter set forth and claimed.

In the accompanying drawings, Figure 1 is 15 a longitudinal sectional view of sufficient of a barrel setting-up or trussing machine to illustrate my invention. Fig. 2 is a transverse section on the line 1 2, Fig. 1. Fig. 3 is a perspective view of the exhaust-pipes and fan 20 forming part of the machine, and Fig. 4 is a view illustrating a modification.

The machine may be similar in general construction to many of those heretofore devised, my invention relating solely to the means for 25 retaining the barrel-heads in position on the grooved stave-guiding heads of the machine.

A is one of the end frames of the machine; B B' B'', tie-rods extending from one end frame, A, to the other; C C, the grooved stave receiving and guiding heads; and D, one of the hoop-driving heads adapted to travel on the tie-rods B B' B'', these heads carrying the hoop-drivers d and being operated by feed-screws d', one only of which is shown in the drawings.

35 The heads C C have stave-receiving grooves c c, into which the staves are fed from the ways e e at the rear of the machine, and on the face of each head C is formed a flange, f, against which the head x of the barrel is seated.

40 I form in the center of each stave-receiving head an opening, F, and to each head I attach a pipe, G, which I prefer to bend upward, as shown, so that it may communicate with a longitudinal pipe, H, which extends to an exhaust-fan, I, driven by any suitable means.

45 Each pipe G has, in the present instance, a flexible portion to allow its lower end to accommodate itself to the movements of the head C.

50 At the end of the pipe H, opposite the end

connected to the exhaust-fan, is a regulating-valve, h, by which the partial vacuum in the pipe G can be regulated. Thus when the valve is fully opened, air can enter the pipe H in quantity almost sufficient to supply the fan I, 55 whereas if the valve h is closed a partial vacuum may readily be maintained in the pipe, supposing, of course, that the openings in the heads C are closed.

When a barrel is to be set up, the fan I is 60 started, and the heads x x of the barrel are placed centrally upon the heads C C bearing upon the flanges f, which may, if desired, be packed to insure a reasonably tight joint. The partial vacuum maintained in the pipes H and 65 G causes the pressure of air upon the barrel-heads to hold the latter firmly upon the stave-receiving heads; but said barrel-heads can be moved to one side or the other to center them as the staves are fed around them; or the heads 70 may be forced from the heads C when subjected to sufficient strain, there being no positive locking of the barrel-heads to the heads C. The speed of the fan and the adjustment of the valve h are such as to maintain in the pipes G 75 and H a partial vacuum sufficient for the purpose intended. In a certain class of barrels, however—those, for instance, in which oil is shipped—the barrels are stowed upon their sides with the bung-hole on top, and the grain 80 of the wood in the heads must be vertical, and as in making this class of barrels the bung-hole is bored in a certain one of the staves prior to the setting up of the barrel the grain of the wood in the head must bear a certain relation to the stave having the bung hole. In setting up this class of barrels, therefore, the heads x are always placed upon the heads C of the machine in a certain position, and in order to prevent them from being turned around by 85 the staves as the latter are fed into the machine I provide each of the heads C with a number of small projecting pins, n, which engage with the barrel-heads and prevent the same from turning. The staves are so fed into 90 the machine that the stave in which the bung-hole is bored is in line with the grain of the wood composing the heads, and the conditions above referred to are secured.

In Fig. 4 I have shown in place of the suc- 95 100

suction-pipes and fan a cylinder, F', having a piston, f', which may be connected by a piston-rod to any suitable operating device on the machine, thus accomplishing the purpose 5 of the suction-pipes and fan, the latter, however, being preferred.

Having thus described my invention, I claim and desire to secure by Letters Patent—

1. The combination of the stave-receiving heads of a barrel trussing or setting-up machine with suction or draft apparatus, whereby the heads of the barrel may be retained on the stave-receiving heads by pressure of air, all substantially as specified.
- 15 2. The combination of the stave-receiving heads having flanges forming bearings for the barrel-heads, with suction or draft apparatus, whereby the air may be exhausted from the

space within said flanges, all substantially as specified.

3. The combination of the stave-receiving heads, the fan, the main draft-pipe, and branch pipes communicating with each head, all substantially as specified.

4. The combination of the stave-receiving heads, the draft-pipes, and a leakage-valve for admitting air to the latter, all substantially as specified.

In testimony whereof I have signed my name to this specification in the presence of two subscribing witnesses.

GEORGE M. NEWHALL.
